UNITED STATES PATENT OFFICE.

WILLIAM L. HARRIS, OF LEXINGTON, KENTUCKY, ASSIGNOR OF ONE-HALF TO ANDREW HAGAN, OF LEXINGTON, KENTUCKY.

AUTOMATIC FIRE-EXTINGUISHING APPARATUS.

1,234,469.

Specification of Letters Patent.

Patented July 24, 1917.

Application filed November 22, 1916. Serial No. 132,859.

To all whom it may concern:

Be it known that I, WILLIAM L. HARRIS, a citizen of the United States, residing at Lexington, in the county of Fayette and State of Kentucky, have invented certain new and useful Improvements in Automatic Fire-Extinguishing Apparatus, of which the following is a specification, reference being had therein to the accompanying drawing.

10 This invention relates to certain new and useful improvements in an automatic fire extinguishing apparatus, and is especially adapted to be used in connection with dry cleaning plants employing rotary dry cleaning machines such as washing machines, and centrifugal extractors, the object being to provide an apparatus in which a sprinkling system is employed controlled by a destructible releasing device whereby the fire extinguishing apparatus will be automatically set in operation in order to extinguish the fire in the dry cleaning plant by sprinkling the machine with an extinguishing fluid.

Another object of my invention is to provide a fire extinguishing apparatus which can be readily installed in any well known makes of dry cleaning apparatus now in use, and one in which steam or a chemical fluid can be employed as an extinguishing medium.

Another object of the invention is to provide a fire extinguishing apparatus in which the fluid supply pipe is provided with a valve normally held in closed position and adapted to be actuated by the releasing of an actuating rod which is normally held in set position and is released by a releasing device employing an inflammable material for releasing a pivoted latch in order to allow the actuating rod to open the valve in order to supply fluid to the machine, additional means being provided for closing an electrical circuit for indicating the location of the fire or sounding an alarm.

45 A still further object of the invention is to provide a releasing device for the extinguishing apparatus which is exceedingly simple and cheap in construction and one in which a pivoted latch is normally held over a catch by a member arranged in the path of said latch, said member resting on an inflammable material which when consumed allows the latch to move off of the catch in order to release the actuating rod 50 so as to actuate the valve.

Another and still further object of my invention is to provide a fire extinguishing apparatus which is capable of being used in connection with various forms of machines, the releasing device being mounted 60 within a box or frame protected by a foraminated cover in order to prevent the pivoted latch from being accidentally disengaged from the catch.

Other and further objects and advantages 65 of the invention will be hereinafter set forth and the novel features thereof defined by the appended claims.

With these objects in view,

Figure 1 is a top plan view partly broken 70 away illustrating the application of my invention to a dry washing machine.

Fig. 2 is a side elevation of the same.

Fig. 3 is a top plan illustrating the application of my invention to a centrifugal 75 extractor.

Fig. 4 is a side elevation of the extractor showing the position of the extinguisher.

Fig. 5 is a top plan view of the releasing device showing its connection with the extinguishing fluid controlling valve.

Fig. 6 is a top plan view of the releasing device with the foraminated cover in open position showing the pivoted latch held in position over the catch by the inflammable 85 material.

Fig. 7 is an edge view of the pivoted latch showing the inflammable material removed.

Fig. 8 is an end view of the releasing device.

Fig. 9 is a plan view of an arm carried by the valve actuating lever.

Fig. 10 is a plan view of the finger carried by the spring actuating rod.

Fig. 11 is a plan view of an inflammable 95 covering for the releasing device, and

Fig. 12 is a side elevation of the pressure tank.

Like numerals of reference refer to like parts in the several figures of the drawing.

In constructing the releasing device in accordance with my invention, I employ a rectangular frame or box 1 preferably formed of sheet metal having a centrally disposed supporting plate 2 on which is pivotally mounted a lever 3 which has connected to one end thereof a pivoted latch 4 adapted to engage a catch 5 carried by a centrally disposed plate 2, said latch being connected to the frame 1 by a coil spring 6 110

which normally has a tendency to hold the latch out of engagement with the catch as will be hereinafter fully described. The pivoted latch 4 is provided with a lateral apertured extension 7 provided with a guideway 8 in which is adapted to be arranged an inflammable strip 9 preferably formed of celluloid which is preferably provided with an opening adapted to register with the opening of the extension 7, but of a small diameter, and over which is mounted a retaining member 10 secured within a block 11, carried by the frame 1 by a set screw 12, as clearly shown in dotted lines in Fig. 6, whereby the pivoted latch 4 will be normally held in position over the catch 5. When the inflammable material is consumed, the retaining member 10 is free to pass through the aperture of the extension 7 so as to release the pivoted latch and the spring 6 will draw the latch off of the catch 5 so as to oscillate the lever 3.

Pivottally connected to the opposite end of the lever 3 is an actuating rod 13 which extends through an opening formed in the frame 1 and through a fixed element 14 of the cleaning apparatus to which the device is applied, and is provided with an adjustable finger 15 at its end provided with a collar carrying a set screw for holding the same in adjusted position on the actuating rod. Disposed between the fixed element 14 and an adjustable sleeve 16, mounted on the actuating rod 13, is a coil spring 17 normally compressed when the device is in the position as shown in Figs. 5 and 6 so that when the inflammable material burns so as to release the pivoted latch, the actuating rod 13 is moved longitudinally, by the action of the spring, whereby a spring actuated valve rod is provided as will be hereinafter fully described.

The finger 15 carried by the spring actuated rod 13 is slidably mounted within a slotted arm 18 carried by a valve lever 19 pivotally mounted on a bracket 20 extending from a valve casing 21 or a fluid supply pipe, said valve lever being pivotally connected to the valve stem 22 as clearly shown so that the valve will be opened when the actuating rod is released in order to allow the extinguishing fluid to pass through the supply pipe to the spraying devices. The construction of valve can be varied without departing from the spirit of my invention, and in order to provide means for indicating the location of the fire, or for warning the operator that a fire exists, I provide a circuit closing device 23 in connection with the valve lever so that a bell can be rung or an indicator actuated when the valve is opened.

In order to provide means for protecting the releasing device, I provide the frame 1 with a pivoted frame 24 having a foraminated covering 25 as clearly shown in Fig. 5.

A strip of inflammable material 26 is preferably arranged within the frame between the foraminated covering, and the latch which is provided with longitudinal and transverse slits, the intermediate portions of which are turned up as shown.

In the application of the device as shown in Figs. 1 and 2, 27 indicates the fluid supply pipe which extends from a suitable source of supply such as a steam boiler or a pressure tank 28 as shown in Fig. 12, which is adapted to be used when a chemical fluid is employed as an extinguishing element. The particular construction of fluid tank can be varied although as shown, the pressure line is connected to the tank by a check valve and extends downwardly into the tank in order to agitate the liquid within the tank, said tank having an outlet pipe at the bottom thereof.

Arranged on the supply pipe 27 is the valve casing 21 which is connected to the releasing device in the manner above described, said pipe extending into the washing machine and is provided with perforated branches 29 which can be arranged at any desired point so as to spray the fluid horizontally toward the center of the machine, some of said branches being arranged to spray down into the machine and toward the top of the opening. I do not wish to limit myself to the manner of arranging these pipes within the machine as the main object of my invention is to provide an automatic fire extinguisher in which the supply pipe terminates in a series of branches arranged within or adjacent the machine for extinguishing the fire therein, said pipe having a valve controlled by a releasing device.

In the application of my improved fire extinguisher as shown in Figs. 3 and 4, 30 indicates the supply pipe which is provided with circular branches 30' and 31, the branch 30' being disposed within the top of the outside drum having openings for spraying the fluid within the drum and the other branch 31 is arranged to spray down over the outside of the machine toward the center at an angle about thirty degrees, the releasing device being arranged and connected to the valve casing 21 as clearly shown, and when fire occurs in the extractor having an extinguishing apparatus as herein shown and described, the valve will be instantaneously opened in order to allow the extinguishing fluid to be sprayed into and over the machine.

The operation of the fire extinguishing apparatus as herein shown, is as follows: When a fire occurs in or about the machine provided with an extinguishing apparatus, the inflammable material within the frame is consumed, and the pivoted latch is released, the retaining member 10 passing through the opening thereof, the latch being drawn

toward the side of the casing or frame by the spring 6 so as to draw it out of the path of the catch which releases the spring actuated rod 13 and by the action of the spring, 5 the same is reciprocated so as to oscillate the valve lever which opens the valve so as to allow the extinguishing fluid to pass through the supply pipe and to the branches or 10 spraying nozzles and at the same time the circuit is closed so as to indicate the location of the fire or to sound an alarm.

From the foregoing description, it will be seen that I have provided a fire extinguishing apparatus in which a supply pipe 15 is arranged and connected with a series of perforated branches disposed within and above the cleaning machine, said supply pipe having a valve connected with a releasing device which actuates the valve when a fire 20 occurs so as to allow the extinguishing fluid to pass through the supply pipe to the machine.

I claim:

1. In a fire extinguishing apparatus, the 25 combination with a valve controlled supply pipe, of a spring actuated rod having a connection with said valve, a pivoted lever connected to said rod, a latch carried by said lever, a spring for moving said latch in one 30 direction, a retaining member, and destructible means carried by said latch arranged to engage said retaining member.

2. In a fire extinguishing apparatus, the 35 combination with a valve controlled fluid supply pipe, of a spring actuating rod for said valve, a pivoted latch for holding said rod in operative position, destructible means carried by said latch, and a retaining member arranged in the path of travel of the 40 destructible means of said latch.

3. In a fire extinguishing apparatus, the 45 combination with a valve controlled fluid supply pipe, of a lever for actuating said valve, a spring actuated rod having a sliding connection with said lever, and pivoted means including a destructible member for holding said actuating rod in set position.

4. In a fire extinguishing apparatus, the 50 combination with a valve controlled supply pipe, of a spring actuated rod having a connection with said valve, a lever connected to said rod, a spring actuated latch connected to said lever, destructible means carried by said latch, and a retaining member arranged in the path of said destructible 55 means.

5. In a fire extinguishing apparatus, the 60 combination with a valve controlled fluid supply pipe, of a lever connected to said valve, a spring actuated rod having a sliding connection with said lever, a frame, a lever mounted in said frame having a connection with said actuating rod, a pivoted latch carried by the free end of said last 65 mentioned lever, a catch adapted to be en-

gaged by said latch, destructible means carried by said latch, and a retaining member arranged within the frame and adapted to engage said destructible means.

6. In a fire extinguishing apparatus, the 70 combination with a valve controlled fluid supply pipe, of a spring actuated rod having a connection with said valve, a frame, a lever mounted in said frame having a connection with said actuated rod, a catch arranged within said frame, a pivoted latch carried by said lever coöperating with said catch, a spring for moving said latch off of said catch, a destructible member carried by said latch, and a retaining member arranged within the frame engaging said 75 destructible member.

7. In a fire extinguishing apparatus, the 80 combination with a valve controlling lever, of a slotted arm carried by said lever, a spring actuated rod, a finger carried by said rod extending into the slotted arm, a pivoted latch for holding said rod in set position, and a destructible member carried by said latch coöperating with retaining means. 85

8. In a fire extinguishing apparatus, the 90 combination with a valve controlling lever, of an actuating rod having a connection with said lever, a spring for forcing said lever in one direction, a second lever carried by the end of said rod, a catch, a latch carried by said second lever coöperating with said catch for holding said rod in set position, a spring for drawing said latch off of said catch, a destructible member carried 95 by said latch, and a retaining member arranged in the path of said destructible member. 100

9. A fire extinguishing apparatus, comprising a valve controlled fluid pipe having 105 spray nozzles, and a releasing device comprising an actuating rod having a connection with said valve, said releasing device having a pivoted latch for holding said actuating rod in set position, and destructible 110 means for holding said latch.

10. In a fire extinguishing apparatus, the 115 combination with a valve actuating rod, a lever connected to said rod, a catch, a spring actuated latch carried by said lever coöperating with said catch, a destructible member carried by said latch, and a retaining member arranged in the path of said destructible member.

11. In a fire extinguishing apparatus, the 120 combination with a frame, of a lever mounted within said frame, a valve actuating rod connected to one end of said lever, a catch, a pivoted latch connected to the other end of said lever having a guideway, a destructible member arranged within said guideway, a spring for moving said latch off of said catch, and an adjustable retaining member arranged to engage said destructible 125 member. 130

12. In a fire extinguishing apparatus, the combination with a frame, of a lever pivotally mounted within said frame, a spring actuated rod having a connection with one end of said lever, a pivoted latch connected to the opposite end of said lever having an apertured guideway, an inflammable member arranged within said guideway, and an adjustable retaining member arranged to engage said inflammable member for holding said actuating rod in set position.

13. In a fire extinguishing apparatus, the combination with a valve controlled fluid supply pipe, of a spring actuated rod having a connection with said valve, a lever having a connection with said spring actu-

ated rod, a pivoted latch carried by said lever, a catch adapted to be engaged by said latch, a spring for normally holding said latch out of engagement with said catch, a 20 destructible member carried by said latch, and an adjustable retaining member arranged to engage said destructible member for holding said latch in position over said catch.

25. In testimony whereof I hereunto affix my signature in the presence of two witnesses.

WILLIAM L. HARRIS.
